DETACHABLE PLATE FOR CONCEALED MANIFOLDS OF GAS RANGES

Filed May 10, 1927

4 Sheets-Sheet 4

UNITED STATES PATENT OFFICE.

JOSEPH ROY, OF CLEVELAND, OHIO, ASSIGNOR TO AMERICAN STOVE COMPANY, OF ST. LOUIS, MISSOURI, A CORPORATION OF NEW JERSEY.

DETACHABLE PLATE FOR CONCEALED MANIFOLDS OF GAS RANGES.

Application filed May 10, 1927. Serial No. 190,201.

This invention relates to improvements in detachable plate for concealed manifolds of gas ranges and the present invention has relation to stoves which contain a concealed 5 manifold having projecting handles for working the gas valves.

The present improvement is for use also in connection with a concealed manifold having attached gas valves which are also 10 concealed, the handles for operating the gas valves projecting through the front of the range.

In the manufacture of gas ranges having a concealed manifold and concealed gas 15 valves, much trouble has been encountered in their use by reason of the necessity of getting access to the concealed elements, for the purpose of repairing, cleaning, etc.

Heretofore in the use of a concealed manifold, gas valves and their housings, there 20 has been no means by which the parts can be detached, adjusted or cleaned, without disconnecting the entire manifold from the stove.

25 In the use of my present improvement the front of the range in which the manifold, gas valves and their housings are concealed, comprises substantially a rectangular frame having its upper horizontal portion located 30 above the manifold, gas valves and their housings, and a detachable plate located below the upper portion of the rectangular frame that conceals the manifold, valves and their housings from the outside of the range.

35 In carrying out my present improvement, this detachable plate comprises a series of long vertical slots to receive the projecting handles, and also comprises a series of short vertical slots located between the handles to 40 permit access by means of a screw driver from the outside to the usual shutter for regulating the amount of air passing to the burner manifold.

45 By means of this detachable plate it is only necessary to remove a screw at each end and slide the plate downward, causing the handles to move through said slots, when access is permitted to the valves and their housings from the front of the range, thus 50 not necessitating the removal of the whole manifold as usual, nor necessitating the removal of any part of the range excepting the detachable plate.

55 The present improvement also relates to an inner shield for the manifold, the valves

and their housings, whereby the said parts are wholly concealed from the inside as well as the outside. The principal object in providing this shield is as a means of protection to the valves, their housings and also the 60 manifold. This shield serves to protect the valves and their housings from the immediate heat of the burners located in the range, whereby they are not subjected to excessive heat that would cause the valves 65 to tend to freeze or stick, and thereby make them inoperative. The present shield further protects them from the heat by being formed of a double plate having a filling of asbestos or mineral wool, thus forming a 70 non-conductor for the radiated heat from the burners.

Further improvements in the invention here disclosed will be explained in the description of the parts. 75

In the accompanying drawings:

Figure 1 is a perspective view of a gas range showing my present improvement applied thereto.

Figure 2 is a vertical cross section through 80 one of the handle vertical slots.

Figure 3 is a vertical sectional view somewhat similar to Figure 2, taken at one side of the handle slot and showing a screw driver in position for adjusting the shutter 85 for regulating the amount of air mixed with the gas.

Figure 4 is a detached front view of the upper portion of the rectangular frame showing the detachable plate in position on 90 the frame and the handles projecting through the slots of the said plate.

Figure 5 is a horizontal view of Figure 4 looking from the inner side, and showing the shield in position and its cooperating parts. 95

Figure 6 is a view looking at the rectangular frame from the inner side, the shield being removed, exposing the manifold, gas valves and their housings.

This improvement as stated, is on a gas 100 range, such as shown in Figure 1. In this figure an ordinary conventional range is shown with my improvement attached thereto, and also used in conjunction with an oven heat regulator. In this view, 1 indicates what is usually referred to as the open burner construction of the range, though in this instance its top portion 2 is preferably closed, and 3 is the oven and broiler 105 part of the range. 110

The front portion of my improvement on the conventional range, comprises a rectangular frame 4, that forms a marginal construction.

5 In the arrangement here shown, I place the manifold 5 adjacent the upper horizontal portion 6 of the rectangular frame, and below the manifold are a series of valve housings 7 that have upwardly extending communications 8 connected with the said manifold. These housings are preferably conical in shape, as shown and the gas valves (not specifically shown) are correspondingly so shaped.

10 15 It will thus be seen that the manifold is concealed from the front of the stove by the upper horizontal member 6 of the horizontal frame, and for the purpose of concealing said housings 7 and their gas valves 7' from the outer side of the range, I use an improved detachable plate 9. This plate is provided with vertical elongated slots 10 in which the handles 11 of the valves oscillate vertically for opening and closing them; the 20 25 outer portion 12 of the handles are enlarged.

30 For the purpose of enclosing the manifolds, valves and their housings from the inner side of the range, I provide a depending member 13 that has its end 14 located as shown. This member 13 I term a shield and it extends downward a distance substantially to the lower portion of the detachable plate 9. This shield is so shaped as to receive interiorly, an asbestos or mineral wool filling 15, whereby it provides a non-conducting heat member, and thus shields the valve housings and valves from the direct heat of the burners in the housing 1.

40 45 By reference to Figure 2, it will be observed that a horizontal frame 16 extends across the front end of the part 1 of the range, and this member 16 extends downward as shown at 17, forming a rectangular member that is clamped in a manner to be presently described.

50 55 The manifold 5 in this improvement is supported by means of a holder 18. This holder 18 (of which there are two) is provided with a curved portion 19 that fits the inner side of the manifold 5 and extends around under it as shown, while its upper end 20 abuts against the under side of the member 16 and a screw 21 passes through the member 16 and into the part 21, thus serving to unite the parts together. The manifold 5 is clamped between vertically arranged members 22, placed between the manifold and the frame 6, and these members 22 are connected with the flange 17 by means of a suitable screw 23. It will be understood, of course, that the members 22 may be omitted and the manifold clamped directly between the flange 6 and the holder 18. By providing members 22 that consist of simply a rela-

tively narrow vertical strip, the manifold is held out of contact with the part 6, thus making a circulation of air around it.

It will be understood, of course, that gas nipples 24 communicate with the valve housings 7 and that these nipples extend inward into a gas and air mixing member or chamber 25, that is connected with a manifold 26 that extends inward and is operatively connected with the burner, not shown, located in the housing 1. As is usual, the front end of this member 25 has an oscillatory shutter member 26 that is held in its adjustment by means of a screw 27. This member needs to be adjusted to get the proper mixture of air with the gas, and to carry out the idea of the present improvement, the detachable plate 9 has its upper edge provided with short slots 28 that register with openings 29 in the shield, whereby a screw driver 30 may be passed through said slot and said opening and engage the screw 27, thus enabling the shutter to be adjusted from the outside of the range structure.

35 In order to permit the passage of the nipples 24 through the shield, the latter is provided with a plurality of openings 31, the openings being located in proper position for their passage.

40 45 This shield is held in position by means of screws 32 which pass through horizontal slots 33 into the holders 18.

50 55 I adapt my present improvement to be used also in connection with a heat regulator 34, by means of which gas is supplied to an oven burner (not shown), and in this event the heat regulator is connected by a suitable tube 35 to a valve having a handle 12' that is connected with the manifold the same as the other valves. This improvement is especially adapted for use in connection with the oven heat regulator.

60 65 Many ranges are fitted with a lighter, which is not here shown. In the event of an automatic lighter being used, it passes through a short vertical slot 28', thereby adapting this improvement for use with the various types of stoves. The nipple (not shown) for the automatic lighter (not shown), passes through an opening 36 made in the shield 13.

70 75 The plate 9 in the form here shown is made of cast metal, and it may be enameled, but I desire it understood that sheet metal may be used instead of the cast metal.

80 85 It will be observed that the detachable plate is here shown connected with the frame 4 by means of screws 4' passing therethrough, and through lips 5' that extend from the inner edge of the wall 4 of the rectangular frame.

90 95 It will be observed from the drawings and the description that in carrying out my improvement I have the front wall of the housing for the burners, which is referred

to as the open part, constructed rectangular in form. I show the rectangular portion large enough to include a door or other member 37, though that is not essential to the 5 invention since the rectangular portion may be made of a size adapted to receive the detachable plate 9.

Also the valve is so constructed that when the handles 12 are down, the burners are 10 turned off, and below the vertical openings 10 I place the word "Off", and also indicate which one of the burners controls the oven heat regulator.

By this improvement a concealed manifold, valve housings and valves can be readily manufactured and sold, and the same be adapted to be readily repaired or cleaned either by the manufacturer, dealer or user, without the necessity of removing the manifold, which is necessary in other constructions having a concealed manifold that are known to me.

I have described in considerable detail my present improvement, but I desire it to be 25 understood that the specific constructions may, in many details, be varied so long as they are within a fair scope of the appended claims.

Having thus described my invention, what 30 I desire to claim and secure by Letters Patent is:

1. In a gas range having a horizontal burner housing, a horizontal manifold located within the housing, valve housing and 35 valves communicating with the manifold and also located within the housing, valve handles projecting to the outer side of the housing, the said housing having its outer wall comprising an open horizontal frame work 40 having its upper wall above the housings and the valves, and a detachable plate fitting in the said frame wall, said detachable plate having openings for said handles, and means detachably connecting the said plate 45 with the frame wall, whereby the plate may be removed and the valve housing and valves disconnected from the manifold, thereby avoiding the usual necessity of disconnecting the said manifold.

2. A gas range having a horizontal burner structure, the outer vertical wall of said structure having an open horizontal frame, a manifold located within the said frame, valve housings and valves connected with the manifold and also located within the frame, the valves having outwardly extending handles, and a detachable plate fitting within said frame, the said plate having elongated vertical slots with open upper ends to receive 50 the handles, means detachably connecting the said plate with the said frame, whereby the said plate may be removed, exposing the housings and the valves which latter may also be removed without disturbing the said 55 manifold.

3. A gas range having a horizontal burner structure, the front vertical wall of the said structure having a horizontal elongated rectangular open portion adjacent its upper end, a manifold extending horizontally and longitudinally within the said housing and located behind the horizontal upper portion of said frame, valve housings and valves communicating with the said manifold and extending therebelow, valve handles projecting beyond the said frame, and a detachable plate fitting in the said frame and having passageways for the said handles, whereby the said plate may be removed, exposing the 70 housings and the valves for attaching, detaching, or cleaning thereof.

4. A gas range having a horizontal burner housing, the outer wall of the said housing having at its upper portion a rectangular opening, a manifold extending horizontally and longitudinally within the said housing and located substantially back of the upper wall of the said opening, valve housings and valves located below the manifold, and extending opposite said opening, handles projecting outward beyond the said frame and a detachable plate filling the said opening, said plate having upwardly projecting open ended slots whereby it may be attached or detached, when detached, exposing the valves and valve housings whereby they may be attached, detached or cleaned without disturbing the said manifold.

5. A gas range having a horizontal burner housing, the outer vertical wall of said housing having a horizontal opening at its upper portion, a horizontal and longitudinally extending manifold located within the housing, valve housings projecting from the said manifold, valves within the said housings, handles for the valves projecting through the said opening, a detachable plate connected with the said housing and fitting within the said opening, said plate having elongated openings for the movement of the handles and also enabling the said plate to be attached or removed, and when removed, not disturbing the said manifold.

6. A gas range having a horizontal burner housing, a manifold extending longitudinally through the said housing and located adjacent its upper end, valve housings and valves also located within said housing, a shield attached to the housing and embracing the said manifold and housings for the purpose specified, and handles for the valves projecting through the outer wall of the housing, substantially as described.

7. A gas range having a horizontal burner housing, a gas manifold extending longitudinally within the said manifold adjacent the upper end of the valve housings projecting from the said manifold, valves within the housings, valve handles projecting though openings provided in the outer ver-

tical wall of the said housing, and a shield located inside of the manifold and the valves for the purpose of protecting them from the heat of burners located therein, substantially 5 as specified.

8. A gas range having a horizontal burner structure, the outer vertical wall of the said structure provided with openings, a manifold extending horizontally through the said 10 structure and located substantially at its upper end, a valve housing and valves located within the said housing and communicating with the said manifold, a shield located within the housing and at the inner 15 side of the valve housings and manifolds, said shield having openings, the valve housings having nipples projecting through said openings, and the outer vertical wall of the housing having a detachable plate, and the 20 valves having handles projecting through openings in the said plate for the purpose specified.

9. A gas range having a horizontal housing, a manifold extending through the said 25 housing and located at its upper end, valve housings communicating with the said manifold, valves within the housing, a shield located within the said housing to embrace the said manifold and housings between it

and the vertical wall of the gas range housing, nipples extending from the valve housings through the said shield, a gas and air mixer connected with the said nipples, and regulating shutters connected with the said mixers, the said shield having openings located to receive an instrument for regulating the said shutters for the outside of the structure. 30 35

10. A gas range having a horizontal burner housing, a horizontally extending 40 manifold within the housing near its upper end, valve housings varying with the manifold, valves within the said valve housing, handles for the valves projecting beyond the outer wall of the gas range housing, said 45 handles being enlarged at the outer ends, and a detachable plate forming a part of the structure of the vertical wall of the gas range housing, said detachable plate having vertically arranged slots with one end thereof open, valve handles passing through said slots, whereby when the plate is detached the valve housings and valves are exposed 50 for the purpose specified.

In testimony whereof I hereunto affix my 55 signature.

JOSEPH ROY.
